UNITED STATES PATENT OFFICE.

DAVID CALVIN MILLER, OF MOUNT BRADDOCK, PENNSYLVANIA.

METALLIC TIE AND RAIL-FASTENER.

1,015,056.

Specification of Letters Patent.

Patented Jan. 16, 1912.

Application filed October 27, 1911. Serial No. 657,050.

To all whom it may concern:

Be it known that I, DAVID CALVIN MILLER, a citizen of the United States of America, residing at Mount Braddock, in the county of Fayette and State of Pennsylvania, have invented certain new and useful Improvements in Metallic Ties and Rail-Fasteners, of which the following is a specification, reference being had therein to the accompanying drawing.

This invention relates to metallic ties and rail fasteners, and the primary object of my invention is to furnish a tie of the I-beam construction with novel fasteners for preventing the alinement of rails, without resorting to the use of bolts and nuts.

Another object of this invention is to provide a tie with fasteners that can be easily and quickly installed to prevent vertical and lateral displacement of the rails of a track.

A further object of this invention is the provision of simple and effective means for cushioning rails upon a metallic tie, whereby said rails will possess sufficient elasticity to compensate for the vibrations set up by heavy rolling stock.

With the above and other objects in view the invention resides in the novel construction, combination and arrangement of parts to be hereinafter specifically described and then claimed.

Reference will now be had to the drawings wherein there are illustrated the preferred embodiments of the invention, but it is to be understood that the structural elements are susceptible to such changes as fall within the scope of the appended claims.

In the drawings, like numerals of reference denote corresponding parts throughout the several views in which—

Figure 1 is a side elevation of a portion of a metallic tie provided with a rail fastener in accordance with this invention. Fig. 2 is a similar view partly broken away and partly in section. Fig. 3 is a plan of a portion of the tie and the rail fastener. Fig. 4 is a perspective view of a detached fastener. Fig. 5 is a perspective view of a portion of a tie in accordance with this invention. Fig. 6 is a side elevation of a portion of a tie provided with a modified form of fastener. Fig. 7 is a plan of the same. Fig. 8 is a perspective view of a detached modified form of fastener. Fig. 9 is a perspective view of a detached cushioning plate and Fig. 10 is a perspective view of a detached retaining bar.

The reference numeral 1 denotes a tie of the I-beam construction having base flanges 2 and top flanges 3, adjacent to the ends of the tie, are provided with oblong openings 4 in communication with oblong slots 5 formed in the web of the tie adjacent to the top flanges 3.

The top flanges 3 at a point intermediate the openings 4 support the base flanges 6 of a rail 7. Engaging the sides of said rail are the heads 8 of fasteners 9 slidably mounted upon the top flanges 3. The fasteners 9 correspond in width to the tie and the longitudinal edges of said fasteners are provided with inwardly projecting flanges 10 to engage under the top flanges 3. The head of each fastener is cut away, as at 11 to provide clearance for the base flanges of the rail and the head 8 is reinforced relatively to the fastener 9 by a longitudinal web 12. The outer end of the web is slotted, as at 13 to provide ears 14 that are apertured, as at 15.

Engaging in the openings 4 and the slots 5, under the flanges 3, are the depending hooks 16 of clamping bars 17. Said bars have the ends thereof beveled, as at 18 to engage angle spacing washers 19 arranged in the slotted ends of the webs 12. The ends of the clamping bars retain the fasteners in engagement with the rail 7 and said bars are retained in engagement with said fasteners by cotter pins 20 arranged in the apertures 15 of the ears 14.

Reference will now be had to Figs. 6 to 10 inclusive illustrating a fastener provided with means for cushioning a rail 21. A cushioning plate 22 is interposed between the base flanges 23 of the rail 21 and the flanges 3 of the tie, the fasteners 24 being made of a sufficient depth to provide clearance for said plate. The confronting ends of the fasteners are slotted or provided with longitudinal sockets 25 to accommodate the ends of retaining bars 26. The bars 26 engage the ends of the plate 22 and prevent displacement of said plate.

Associated with the plate 22 in cushioning the rail 21 are cushioning blocks 27 arranged in the heads 28 of the fasteners 24, said blocks, together with the plate 22, being made of wood or other yieldable or compressible material. The fasteners 24 are held in engagement with the tie similar to the fasteners 9.

It is thought that the manner of assem-

bling the fasteners upon the tie will be apparent without further description, and I would have it understood that the tie and fasteners can be used in connection with industrial and other railways.

5 What I claim is:—

1. In a metallic tie and rail fastener, the combination with a tie of the I-beam construction having the top flanges thereof provided with openings, and a rail adapted to be supported by the top flanges of said tie, of fasteners slidably mounted upon the top flanges of said tie and engaging the sides of said rail, clamping bars having hook-shaped 10 ends engaging in the openings of said tie, and means including cotter pins for holding the opposite ends of said bars in engagement with said fasteners.
- 15 2. In a metallic tie and rail fastener, the combination with a tie of the I-beam construction having the top flanges thereof pro-

vided with openings, and a rail adapted to be supported by said tie, of a cushioning plate interposed between said rail and the top flanges of said tie, fasteners slidably mounted upon the top flanges of said tie and engaging the sides of said rail, retaining bars having the ends thereof mounted in said fasteners for retaining said cushioning plate upon said tie, clamping bars having the outer ends thereof anchored in said openings, and means carried by the outer ends of said fasteners for holding the inner ends of said clamping bars in engagement therewith.

25 30 35 In testimony whereof I affix my signature in the presence of two witnesses.

DAVID CALVIN MILLER.

Witnesses:

JAMES L. HAZEN,
HENRY C. BUNTING.
